ATTACHMENT PLUG CAP

Augustine H. Massey, Stratford, Conn., assignor
to Columbia Phonograph Company, Inc.,
Bridgeport, Conn., a corporation of New York

Application July 21, 1932. Serial No. 623,803

3 Claims. (Cl. 173—361)

This invention relates to new and useful improvements in attachment plug caps and has for an object to provide an attachment plug cap adapted to mount contact fingers or blades having different distances between their mounting and binding screws.

Other objects and advantages will become apparent from a consideration of the following detailed description taken in connection with the accompanying drawing wherein a satisfactory embodiment of the invention is shown. However, it will be understood that the invention is not limited to the exact details disclosed but includes all such variations and modifications as fall within the scope of the appended claims.

In the drawing:

Figure 1 is a side elevational view of an attachment plug cap in accordance with the invention;

Fig. 2 is a bottom plan view of the cap;

Fig. 3 is a similar view the contact fingers being omitted; and

Fig. 4 is a sectional view taken substantially along the line 4—4 of Fig. 2.

Referring in detail to the drawing the reference character 5 indicates in its entirety the improved cap moulded from any suitable insulating material. Cap 5 is hollow and includes a skirt portion or wall 6 at the inner side of which at diametrically opposite points is provided a pair of lugs or enlargements 7 each equipped with an opening or recess 8 for the reception of a mounting screw.

Also at diametrically opposite points at its inner side the body is provided with enlargements or shoulder portions 9 adjacent one side of which are upstanding lugs or tips 10, the purpose of which will later appear. Extending from the outer edges of the enlargements or shoulders 9 are flange like portions or walls 11 of the height of the portions 9. It will be noted that the flange like portions or extensions 11 each extend in the direction of one of the lugs 7 and that such portions are arranged in spaced relation to the walls 6 of the cap.

The contact members are of the usual construction and each include a finger or blade 12 carried by a mounting portion or plate 13 through which is passed a mounting screw 14 entering into one of the openings or recesses 8 of one of the lugs 7. It will be understood that two contact members are employed in connection with each cap 5, one cap contact member being anchored to each of the lugs 7 whereby the members are spaced the proper distance apart.

Each of the plates 13 carries a binding screw 15, the said binding screws being arranged in

spaced relation to the mounting screws 14 and being adapted to secure the ends of conductors (not shown) to the contact members. Such conductors are, of course, brought into the cap through the usual opening 16 therein.

60

Ordinarily, attachment plug caps are provided with openings to receive the binding screws 15, the said openings being provided in enlargements moulded at the inner side of the body and the said openings being spaced from the mounting screw opening 8 a distance equal to the distance between a mounting screw and a binding screw. However, the contact members made by different manufacturers do not have their mounting screws and binding screws spaced the same distance apart. That is, in the product of one manufacturer the two screws may be spaced apart a distance greater than or less than the distance between the screws in the product of another manufacturer.

70

With the present device the contact members are disposed with their plate portions 13 engaging the lugs 7, the shoulder portions 9 and the extensions 11 and the mounting screws 14 are driven into the openings 8 in the lugs 7. The binding screws 15 will be disposed in the spaces between the portions 11 and the side walls 6 of the body. Here attention is called to the fact that the portions 9, extensions 11 and adjacent portions of the wall 6 combine to form open sided pockets for the reception of the lower portions of the binding screws 15.

75

It is to be noted that said portions 11 are of appreciable length and form open sided pockets as above described and it will therefore be noted 90 that the cap 5 is adapted to have contact members mounted therein irrespective of slight differences in the distances between the mounting and binding screws thereof. That is, the screws 14 and 15 may be somewhat closer together than 95 as shown or they may be spaced farther apart. There will be no wall or portion to interfere with the insertion of the binding screws and yet the plates 13 of the contact members will be adequately supported on the lugs 7 and 9 and the portions or extensions 11 of the lugs 9.

100

As a matter of fact the plates 13 need not all be of the same length since should they fall short of the lugs 9 they will be supported on the upper edges of the portions or extensions 11. In addition to assisting in supporting the plates 13 the portions or extensions 11 also form a partial barrier enclosing the lower portions of the binding screws 15 whereby said portions will not be exposed below the plates 13 of the contact mem- 110

ber. The raised portions or tits 10 are to assist in maintaining the exposed portions of a lead wire under the head of a binding screw to which the wire is connected.

5 From the foregoing description it will be seen that by providing open sided pockets formed by the extension or wall like portion 11, rather than recesses for the reception of the lower portions of the binding screws the improved cap is adapted 10 to receive contact members of slightly different sizes or construction. The variations in sizes or the variations in the distances between the binding and mounting screws of these devices is relatively slight and all known variations are taken 15 care of by the structure disclosed. Therefore, it will be seen that the improvement disclosed makes the present cap substantially universal as regards the mounting of contact members. Further, there is some savings in the material from 20 which these caps are moulded and in addition the tools employed in the moulding operations are somewhat less complicated and cheaper to make.

Having thus described the invention, what is claimed is:

25 1. In an attachment plug cap, a hollow body of insulating material, said body having a pair of lugs moulded integral therewith at its inner side and provided with openings for the reception of the mounting screws of contact members, and 30 L-shaped lugs formed with said body and each having an arm extending radially with respect to the walls of the body and an arm in spaced

relation to said walls and providing with said walls open sided pockets for the reception of the binding screws of the contact members.

2. In an attachment plug cap, a hollow body of insulating material, said body having a pair of lugs moulded integral therewith at its inner side and provided with openings for the reception of the mounting screws of contact members, other lugs formed with said body in spaced relation to said first lugs, said other lugs having portions extending toward said first lugs and in spaced relation to the walls of said body, and said extending portions co-operating with the walls of said body to provide open sided pockets for the reception of the binding screws of the contact members. 80 85 90

3. In an attachment plug cap, a body of insulating material including an annular wall, lugs at the inner side of said wall and arranged diametrically opposite each other provided with openings for the reception of mounting screws of contact members, other lugs at the inner side of said wall and arranged diametrically opposite each other and at points about said walls midway between said first lugs, said second lugs including portions extending toward said first lugs and in spaced relation to the walls of said body whereby said extending portions with the walls of the body provide open sided pockets for the reception of the binding screws of the contact members. 95 100 105
